TRANSFORMER

Albert W. Friend, Collingswood, N. J., assignor
to Radio Corporation of America, a corporation
of Delaware

Application October 2, 1945, Serial No. 619,871

2 Claims. (Cl. 315—27)

1

The present invention relates to electrical transformers, especially coupling or output transformers of the type employed in television receiving systems which include a cathode ray image-reproducing tube. More particularly, the invention relates to means whereby a television coupling or output transformer may be utilized to regulate the size of the image raster scanned by the electron beam of such a cathode ray image-reproducing tube.

The invention herein disclosed constitutes a further development of the inventions set forth in my copending applications for U. S. Letters Patent, Serial No. 619,869, now Patent No. 2,451,026, and Serial No. 619,870, filed concurrently herewith, and entitled "Television system" and "Transformer" respectively.

Television receiving systems utilizing the principle of electromagnetic deflection of a cathode ray scanning beam normally include a power output tube which is adapted to deliver cyclically varying current, a portion of each cycle of which varies in a substantially linear manner with respect to time, through a coupling transformer to a pair of cathode ray beam deflection coils incircling the neck of an image-reproducing cathode ray tube. Since the instantaneous angle of deflection of the cathode ray scanning beam is a function of the instantaneous strength of the magnetic deflecting field in the vicinity of the deflection coils, and since this deflecting field is, in turn, dependent upon the amplitude of the current flowing through the deflection coils at such time, it follows that a change in the peak amplitude of the current flowing through the deflection coils will produce a change in the size of the image raster scanned by the cathode ray beam.

In my two copending applications referred to above, there is set forth means for eliminating the necessity for the separate variable inductor which is normally shunted across several turns of the secondary winding of the coupling transformer to thereby control the peak amplitude of the deflection current for the purpose of image size regulation. In one of these disclosures, this may be achieved by forming in the transformer core an aperture which is adapted selectively to receive a slug of magnetic material. This slug, by varying the permeability of the core as it enters the aperture, changes the overall impedance of the transformer, and hence the peak amplitude of the cyclically varying current flowing through the cathode ray beam deflection coils. In the disclosure of the other mentioned applica-

tion, the center leg of the transformer core (that is, the leg around which the coils are wound) is separated into two portions, one of which is arranged to be movable. By an actuation of this movable leg portion, a change in the overall impedance of the transformer is brought about.

In this last-mentioned application, three tubular transformer coil windings of different diameters are utilized, consisting of one primary winding and two separate secondary windings. These elements are arranged so that one of the secondary windings surrounds the center leg of the transformer core. The primary winding overlies, and is insulated from, this secondary winding, while the other of the two secondary windings overlies, and is insulated from, the primary winding. As a result of such a construction, any change in the impedance of the transformer due to variations in the position of the movable core leg portion will have an influence upon the currents produced in each of the separate secondary windings which is approximately proportional to the turns ratio therebetween.

When a transformer such as described above is employed in a television system, the primary winding is customarily connected in the anode-cathode circuit of the power output tube. One secondary winding may be connected across the cathode ray beam deflection coils, while the other secondary winding may be used to step up the surge voltage developed across the transformer during the retrace periods of the cathode ray beam, so that this voltage may be rectified and employed as the second anode potential for the kinescope, either directly or through a voltage doubling or "multiplying" circuit.

This step-up secondary winding, mentioned above, must consist of a relatively large number of turns in order to develop the high second anode potential required. In such a case, however, it will be appreciated that any change in the impedance of the transformer due to an adjustment of the movable core leg section for the purpose of image size control will have a very appreciable effect on the voltage developed across this step-up secondary winding, or, in other words, such an adjustment of the transformer for the purpose of size control will cause undesirable variations in the accelerating potential applied to the cathode ray image reproducing tube which is commonly termed a "kinescope."

One object of the present invention, therefore, is to provide, in a television receiving system in which the accelerating potentials for the image-reproducing cathode ray tube are obtained by

rectifying the surge voltage developed across a step-up winding on the coupling transformer during the retrace periods of the cathode ray beam, means whereby the coupling transformer may be modified to act as an image size control device, and further means whereby the size control function of the coupling transformer may be performed without introducing any excessive variations into the cathode ray tube accelerating potentials as derived from across the said step-up winding.

Another object of the present invention is to provide an improved form of image size control for television receivers.

A still further object of the invention is to provide a multi-winding transformer in which variations in the electromagnetic coupling between certain of the windings will affect to a much lesser degree the electromagnetic coupling between certain other of the windings.

Other objects and advantages will be apparent from the following description of preferred forms of the invention and from the drawings, in which:

Fig. 1 is a sectional view of a transformer constructed in accordance with the present invention;

Fig. 2 is a top plan view of the transformer of Fig. 1;

Fig. 3 is a diagram of one possible circuit in which the transformer of Fig. 1 might be employed;

Fig. 4 is a simplified circuit equivalent from an impedance standpoint to that of Fig. 3; and

Fig. 5 is a perspective view, in section, of a modification of the transformer of Fig. 1.

In Figs. 1 and 2 is shown a coupling or output transformer, generally indicated by the reference character 10. The core of transformer 10 is composed of two matching frame pieces 12 and 14, best shown in Fig. 2, and two central leg sections, or slugs, 16 and 18. Each of these core components 12, 14, 16 and 18 is preferably molded of some suitable finely divided ferromagnetic material, such as powdered or comminuted iron, in combination with a binder. The matching frame pieces 12 and 14 are each preferably rectangular in shape, with the central portion of the two long sides of each frame piece being curved away from the plane of the frame piece in such a manner that the inner surface of each of these curved portions is approximately semi-cylindrical in shape. The curved central portions of one side of each of the frame pieces 12 and 14 are respectively designated as 12a and 14a in Fig. 2, the curved central portions of the other, or lower, side of each of the frame pieces being respectively identical to these portions 12a and 14a, but not being visible in Fig. 2 due to the manner of taking the plan view. However, when the matching frame pieces 12 and 14 are in face-to-face relation, as shown in Fig. 2, then the inner surfaces of curved portions 12a and 14a together define an aperture of substantially cylindrical outline, as do also the inner surfaces of the curved portions (not shown) of the other, or lower, long sides of the frame pieces 12 and 14.

The central leg section, or slug, 18 is cylindrical in shape, and is so dimensioned as to fit securely but movably in the aperture of cylindrical outline defined by the curved core portions 12a and 14a. Similarly, the cylindrical central leg section, or slug, 16 is so dimensioned as to fit securely in the aperture defined by the curved portions of the other, or lower, long sides of the frame pieces 12 and 14 (see Fig. 1).

Slug 16 is intended to remain clamped in a selected position between the frame pieces 12 and 14, with a predetermined percentage of the slug extending within the core frame and toward the slug 18. The latter slug 18, on the other hand, is intended to be movable relative both to the slug 16 and to the frame pieces 12 and 14, so that the dimensions of the air gap 20 between slugs 16 and 18 may be varied.

The means for moving the slug 18 relative to the slug 16 are shown in Figs. 1 and 2. A screw 22 is embedded in, or otherwise securely affixed to, the slug 18. This screw 22 passes through a threaded opening in a support 24, the latter being positioned apart from the core frame pieces 12 and 14 by two spacers 26 and 28. A plurality of screws 30 secure support 24 to the spacers 26 and 28.

The core frame pieces 12 and 14 are held in face-to-face relation, as well as against the spacers 26 and 28, by means including two pairs of brackets 32 and 34 respectively. Two pairs of screws 36 and 38 respectively pass through the two pairs of brackets 32 and 34. When the screws 36 and 38 are tightened, they tie the various core elements and slug-adjusting means into a unitary transformer structure, as shown in Figs. 1 and 2.

Three disk-shaped coil windings P, S₁ and S₂ (representing the primary and the assumed two secondary windings, respectively) are positioned so that their planes are in substantially parallel relation with respect to each other, and so that they are approximately normal to the longitudinal axis of the cylindrical core leg sections 16 and 18, as best shown in Fig. 1. All three coils are preferably wound on an insulating support or tube 39, which is slightly larger in diameter than the slugs 16 and 18, and so disposed as to be substantially coaxial with the slugs. As a result of this arrangement, the slug 18 is free to move axially within the tube 39 in response to an actuation of adjusting screw 22.

The coil P, comprising the primary, or input, coil winding of the transformer 10, is disposed intermediate the two coils S₁ and S₂, as shown in Fig. 1. Coils S₁ and S₂ each comprise a secondary, or output, coil winding of transformer 10.

The coils P, S₁ and S₂ are positioned relative to the slugs 16 and 18 so that the air gap 20 formed by the slugs lies between the primary coil P and one of the secondary coils, or S₂ in the example illustrated. This has the effect, when current is flowing in the primary coil P, of varying the electromagnetic coupling between the coils P and S₂ (in response to a variation in the dimensions of the air gap as a result of an actuation of screw 22) without affecting, to an appreciable degree, the electromagnetic coupling between the coils P and S₁. This action is due primarily to the flux leakage between the coils P and S₂ and will be more fully discussed hereinafter in connection with the circuit of Fig. 4.

Fig. 3 shows one possible circuit in which the transformer of Figs. 1 and 2 might be employed, although it will be clearly understood that this particular circuit is being given merely as an example, and that the transformer of the present invention is suitable for use in numerous systems where it is desired to vary the coupling between two portions of a circuit without appreciably varying the coupling between one of these portions and a third portion.

Fig. 3 shows a cathode ray beam deflection circuit including a power output tube 40 having at

least an anode, a cathode, and a control electrode. Power tube 40 is adapted to deliver, when voltage variations having a waveform such as indicated by the reference character 42 are applied between the cathode and control electrode thereof, cyclically varying current, a portion of each cycle of which varies in a substantially linear manner with respect to time as shown by the sawtooth current waveform 44, to a pair of cathode ray beam deflection coils 46 through the output or coupling transformer 10 (shown schematically in Fig. 3).

The primary winding P of transformer 10 is connected in the output, or anode-cathode, circuit of power tube 40. The secondary winding S₁ steps up the voltage developed across the primary winding P for application to a high-voltage surge-type rectifier 48 which may, for example, be of the type set forth in a copending application of Otto H. Schade, Serial No. 578,678, filed February 19, 1945, now Patent No. 2,439,223. The output of rectifier 48 is applied to the accelerating electrode of an image-reproducing cathode ray tube of kinescope 50.

The secondary winding S₂ of transformer 10 is wound in a direction opposite to that of both windings P and S₁. A damper tube 52, in series with a parallel resistance-condenser combination 54, is connected across the secondary winding S₂. Damper tube 52, together with the resistance-condenser combination 54, prevents oscillations in the circuit by acting as a switch which closes at the end of the return, or snap-back, portion of each cycle of the sawtooth current wave 44, or, in other words, at the beginning of each deflection cycle. The switching operation of tube 52 causes a current to flow therethrough which is of such waveform as to assist the power tube 40 in producing the desired linear current variation through the deflection coils 46. The operation of such a damper tube is set forth in U. S. Patent No. 2,309,672 granted February 2, 1943, to Otto H. Schade, and hence will not herein be described in detail.

The horizontal cathode ray beam deflection coils 46 preferably form part of a yoke assembly (not shown) encircling the neck of the conventionally represented kinescope 50. As illustrated in Fig. 3, the series combination of damper tube 52 and resistance-condenser combination 54, as well as the horizontal deflection coils 46, are connected in parallel inter-relation across the secondary winding S₂ of transformer 10.

By varying the dimensions of the air gap 20 through adjustment of screw 22, the electromagnetic coupling between the two coils P and S₂, on opposite sides of the gap 20, is altered. This results in a change in the peak amplitude of the sawtooth current wave 44 flowing through the horizontal deflection coils 46. Since the instantaneous angle of deflection of the cathode ray scanning beam of kinescope 50 is a function of the instantaneous strength of the magnetic deflection field which, in turn, depends upon the amplitude of current wave 44, such a change in peak amplitude of current wave 44 produces a change in the size of the image raster scanned by the cathode ray beam.

However, such a variation in the dimensions of the air gap 20 as a result of adjustment of screw 22 does not change to any appreciable degree the electromagnetic coupling between the two coils P and S₁, since the air gap 20 lies on the opposite side of coil P from the coil S₁. The flux linkage between coils P and S₁ is, therefore,

5 relatively constant for such variations in the width of the air gap 20 as would be made under operating conditions.

As one example of the above operation, it has been found in practice that an increase in the width of the air gap 20 which decreases the electromagnetic coupling between coils P and S₂ to such an extent as to decrease the size of the image raster scanned by the cathode ray beam of kinescope 50 by 32%, changes the electromagnetic coupling between coils P and S₁ to such a small degree that the second anode voltage applied to kinescope 50 decreases by only 2%. This approximately constant second anode voltage is also somewhat influenced by the reduction in transformer inductances decreasing the beam return time slightly, which likewise tends to maintain a high voltage value for the pulse generated by the sudden magnetic flux decay.

20 The efficiency of the powdered iron core transformer of the present invention is at a maximum when the horizontal deflection coils 46 form part of a yoke assembly provided with a core structure of approximately the same or an equivalent type 25 of powdered iron material. In such cases, the circuit of Fig. 3 may be represented schematically by the equivalent circuit of Fig. 4, where

L (with transformer 10) = L (without transformer 10, or in other words with the deflection coils 46 being connected directly in the anode-cathode circuit of power tube 40)

L_p = inductance of primary winding P

L_s = inductance of secondary winding S₂

L_y = inductance of deflection yoke including the deflection coils 46, and k = the coupling coefficient.

Using the above terms, it can be shown that

$$40 \quad L_1 = L_2 = (L - k) \cdot L_p$$

$$L_3 = k \cdot L_p$$

and

$$L_4 = \frac{L_p}{L_s} \cdot L_y$$

45 By a positioning of coils P, S₁ and S₂ relative to the air gap 20 in the manner illustrated in Figs. 1 and 2, it can be shown that an increase in the width of the gap 20 will produce a decrease in the value of L₃ (Fig. 4) and a simultaneous increase in the values of L₁ and L₂, or at least an increase in the ratios

$$L_1 \quad \text{and} \quad \frac{L_2}{L_p}$$

55 In other words, the coupling coefficient k between the coils P and S₂ is decreased to correspondingly decrease the peak amplitude of the current wave 24.

50 A modified form of the transformer of Figs. 1 and 2 is shown in Fig. 5. A pair of matching core portions 56 and 58 of hollow cylindrical configuration are each formed with one open end. The open ends of the cylindrical core portions 56 and 58 are then fitted together as shown so as to substantially completely enclose the interior of the core portions.

55 The closed end of each of the core portions 56 and 58 has a centrally located aperture therein to receive the core leg sections, or slugs, 18 and 16 respectively. The slugs 18 and 16, the former being movable, extend toward one another so as to form an air gap 20 therebetween in the same manner as do the slugs 18 and 16 in Fig. 1.

The three coil windings P, S₁ and S₂ have the same positions relative to one another and to the

air gap 20 as in Fig. 1. Hence a variation in the dimensions of air gap 20 will vary the coupling between coils P and S₂ without varying to an appreciable degree the coupling between coils P and S₁. It should be noted, however, that in the construction of Fig. 5 the coils P, S₁ and S₂ are completely enclosed within the interior of the core portions 56 and 58, and hence are protected against the injurious effects of dirt, moisture, or accidental damage, and that the magnetic field incident to the operation of the transformer is totally enclosed by virtue of the continuous enclosing magnetic structure. This reduces stray interfering effects with other apparatus and at the same time provides a substantially better and more complete path for the magnetic flux of the transformer windings.

It will be apparent that the slug-adjusting means of Figs. 1 and 2, including the screw 22 and support 24, may readily be modified so as to be employed to vary the position of slug 19 in the form of the invention illustrated in Fig. 5, without departing from the spirit of the invention.

Having thus described my invention, I claim:

1. Apparatus for regulating the size of the image raster scanned by a cathode ray beam in a television system of the type in which a power output tube is adapted to deliver cyclically varying current, a portion of each cycle of which varies in a substantially linear manner with respect to time, through a coupling transformer to at least one cathode ray beam deflection coil associated with an image-reproducing cathode ray tube, said coupling transformer being provided with a first winding connected in the output circuit of said power output tube, a second winding connected to said cathode ray beam deflection coil, and a third step-up winding designed to provide a source of potential for application to one or more of the accelerating electrodes of said image-reproducing cathode ray tube, said apparatus including a core for said coupling transformer having a portion the position of which is variable, and means for varying the position of said core portion so as to effect a change in the electromagnetic coupling between said first and second transformer windings without appreciably affecting the electromagnetic coupling between said first and third transformer windings, whereby the peak amplitude of the cyclically varying current flowing through the said cathode ray beam deflection coils is altered to result in a change in the size of the image raster scanned by the cathode ray beam, while the potential applied to the one or more accelerating

electrodes of said image-reproducing cathode ray tube is maintained substantially constant in value.

2. Apparatus for regulating the size of the image raster scanned by a cathode ray beam in a television system wherein a deflection output tube is adapted to deliver through an output transformer, energy to a deflecting coil associated with an image producing cathode ray tube, said output transformer including a primary winding connected to be energized by the output tube, at a secondary winding electromagnetically coupled to said primary winding and connected to supply energy to the deflecting coil from the primary winding, a tertiary winding electromagnetically coupled to said primary winding and adapted to provide a source of potential for at least one of the accelerating electrodes of the image producing cathode ray tube, said transformer including a magnetic core a portion of which is adjustable in position relative to the remainder of the magnetic core, the relation of the windings being such that when the position of the adjustable portion of the core is altered the electromagnetic coupling between the primary and secondary windings may be varied without appreciably varying the coupling between the primary and tertiary windings thereby to alter the energy delivered to the deflecting coil without appreciably altering the potential applied to the cathode ray tube accelerating electrode.
